CLAIM

The ornamental design for a portable computer tablet with a touch screen and stylus, as shown and described.

DESCRIPTION

FIG. 1 is a top front and right side perspective view of a portable computer tablet with a touch screen and stylus showing our new design;

FIG. 2 is a top front and left side perspective view thereof;

FIG. 3 is a top plan view thereof on an enlarged scale;

FIG. 4 is a front elevational view thereof;

FIG. 5 is a rear elevational view thereof;

FIG. 6 is a right side elevational view thereof;

FIG. 7 is a left side elevational view thereof wherein the stylus is shown recessed within a snap-in holder pocket; and,

FIG. 8 is a bottom plan view thereof showing a carrying strap attached wherein the partially shown pattern being understood to continue across the indicated surface represents a conventional fabric.

FIG. 3

FIG. 4

FIG. 5

FIG. 6

FIG. 7

FIG. 8
